UNITED STATES PATENT OFFICE

1,988,283

MEANS FOR MAKING SHOES

Fred Maccarone, Brooklyn, N. Y.

Original application December 20, 1933, Serial No. 703,237. Divided and this application June 12, 1934, Serial No. 730,179. In Canada April 25, 1934

6 Claims. (Cl. 12—17)

My present invention relates to matter disclosed in my co-pending applications Serial Nos. 671,109 and 703,237 filed May 15, 1933 and December 20, 1933, respectively, and is a division 5 of the latter application.

A principal object of my invention is to provide improved means for making shoes of the type originally taught in my United States Patent No. 1,569,823, wherein an insole, to which 10 the upper is affixed, includes an integral heel portion, a shank portion, and a ball portion having a central opening therein defining a continuous marginal rand extending from the front of one side of the shank around the toe 15 and to the front of the opposite side of the shank to afford means for initially affixing the upper to the insole, and an outsole is provided having a marginal depression conforming to the rand for receiving the same with the upper 20 attached thereto, whereby the central portion of the inner face of the outsole is disposed flush with the upper surface of the rand.

A further principal object is to provide means 25 for producing an outsole and a complementary insole therefor, whereby the insole and outsole portions of the shoe are patterned and sized at the same time from a single piece of sole material to insure that the insole and outsole portions are of relatively proper shapes and sizes.

30 A further object is to provide a combination pattern and cutting die for rounding the outsole and initially forming an insole for use therewith. Other and further objects will appear from the following specification.

35 Referring to the drawings:

Figure 1 is a plan view of a combination pattern or template and cutting die for rounding an outsole and initially forming an insole for use therewith.

40 Figure 2 is a cross sectional view on a larger scale of the pattern shown in Figure 1, having a piece of the sole material clamped thereto and illustrates the sole rounding operation as well as the initial insole forming operation.

Figure 3 is a fragmental view similar to Figure 2, illustrating a modification of the combination pattern and die.

45 Figure 4 is a plan view of the rounded sole showing incisions therein cut by the pattern blades defining an insole.

Figure 5 is an enlarged section taken on lines 5—5 of Figure 4.

Figure 6 is a plan view of the female portion 55 of a die employed to securely depress the ball

portion of the rounded and incised sole which is shown lying thereon.

Figure 7 is a cross sectional view taken on line 7—7 of Figure 6 and illustrates, on a larger scale, the ball portion of the sole depressed between the male and female die portions. 5

Figure 8 is a longitudinal sectional view illustrating the method by which the rounded and incised sole is split to provide the complementary and properly sized outsole and insole 10 portions.

Figure 9 is a longitudinal section thru the insole portion.

Figure 10 is a longitudinal section thru the outsole portion. 15

Figure 11 is a longitudinal section thru the backing piece employed to support and reinforce the sole during the splitting operation illustrated in Figure 8.

Figure 12 is an inverted plan view of the 20 insole with the upper lasted and secured thereto.

Figure 13 is a longitudinal section taken thru the insole and portions of the attached upper.

Figure 14 is a longitudinal section illustrating the ball tread portion of the shoe with the outsole assembled thereto. 25

Figure 15 is a side elevation of a completed shoe, shown partly in section to reveal the finished relationship of the sole portions.

Figure 16 illustrates in perspective improved 30 means for depressing the sole material, comprising a pair of plates between which the sole material may be positioned and clamped in a sole rounding machine, one of said plates comprising a sole rounding pattern.

Figure 17 is a cross sectional view taken on line 17—17 of Figure 16.

Figure 18 is a perspective illustration of a plate, similar to the upper plate shown in Figure 16, contoured to define an insole, and carrying a marginal blade for incising and initially forming an insole as the material is clamped in the rounding machine. 40

Figure 19 is a sectional view taken on line 19—19 of Figure 18.

In carrying out my present invention I prefer to first incise the sole material to define an insole portion of suitable size, thickness and proportions, and then to round the outsole from the same piece of material in relation to the 50 insole thus defined.

To accomplish this I may employ a pattern or template, as shown in Figure 1, which comprises a body portion 20 and side and end portions 21 and 21, between which I removably se- 55

cure thin and flexible cutting blades 22—22 by means of countersunk screws 23—23 etc. The blades 22 are positioned and arranged to extend outwardly from the face of the pattern a distance 5 corresponding to the thickness of the insole to be provided and are contoured in conformity with the sole portion of the last on which the shoe is to be assembled.

As indicated in the drawings, it is usually not necessary that the full outline of the insole be incised in the sole material or that the blades 22 extend to accomplish that purpose inasmuch as the insole ordinarily conforms in size and shape to the outsole over the shank and forward portions of the heel and may be formed with the outsole in the sole rounding operation hereafter to be described.

In all other respects the pattern is of the usual type heretofore employed and is provided with holes therethru at 24 and 24 to receive the positioning pins 25—25 of a conventional sole rounding machine, fragmental supporting parts of which are indicated at 26 in Figures 2 and 3.

When the pattern has been positioned on the sole rounding machine, a piece of sole material 27, of uniform thickness, is laid over the pattern and rests upon the cutting edges of the blades 22, whereupon the clamp 28 of the rounding machine is forced down upon the material, causing the blades 22 to cut into the material and firmly holding the material against the face of the pattern during the rounding operation performed by the knife 29, as indicated in Figures 1 and 2. The rounded sole 30 is then taken from the machine and appears with incisions therein as indicated at 32—32 in Figures 4 and 5.

As illustrated in Figure 3, the blades 22 may be made to extend from both faces of the pattern so that alternate faces thereof may be employed to form the sole portions of a mated pair of shoes.

Although I have found the foregoing method of producing the rounded and incised sole 30 economical and otherwise of advantage, it will be understood that the sole as it appears in Figures 4 and 5 may be provided in other ways than that above described for the purposes of carrying out the further operations of my improved method, and that the sole may first be rounded and subsequently incised to define the insole portion if desired.

From the description thus far, it will be apparent that if the sole 30 were now to be split within the depth of the incisions 32, the resulting divisions will comprise two sole portions of different sizes and proportions suitable for use as insole and outsole portions, respectively, of a shoe, and that waste marginal portions corresponding to the material lying outside of the incisions and within the depth thereof will also result.

Before performing such splitting operation, however, I prefer to inflex or depress the central ball tread portion of the rounded and incised sole 30 to a distance somewhat greater than the depth of the incisions 32. This I accomplish by pressing the sole between the male and female elements, 33 and 34 respectively, of a swage or pressing die, as illustrated in Figure 7.

After removal from the pressing die, the sole is reinforced by a perforate backing strip 36 (See Figure 11), which is formed to complement the depressed portion of the sole and is preferably made of a durable and somewhat flexible 75 composition material. The sole thus backed up

is then passed between the rollers 37—37 of a conventional leather splitting machine, the splitting blade 38 of which is positioned to cut within the depth of the incisions 32 and above the bottom of the depressed area 35, so that when the sole has been split its full length, an insole portion 39, perforate centrally of its ball tread portion, and an outsole portion 40, is provided. Waste marginal portions 41 also result from this operation, as will be readily understood.

The insole 39, formed as above, comprises an integral heel portion, a shank portion and a ball portion, the said ball portion having a central opening therein defining a continuous marginal rand 39' extending from the front of one side 15 of the shank around the toe and to the front of the opposite side of the shank.

The insole 39 is next lasted to the upper 42 of the shoe to which it is secured by any of such special adhesives as are well-known in this art, or by other suitable means, preliminary to which a patch 43 may be removably pasted to cover the perforate portion of the insole.

The outsole 40 is then placed in position over 25 the lasted insole and the depressed portion 35 thereof is forced back into its original normal condition, as illustrated in Figure 14. In this manner a marginal depression 40' is defined on the inner side of the outsole which conforms to 30 the rand 39' and received the same with the upper attached thereto, whereby the central portion 35 of the inner face of the outsole is disposed flush with the upper surface of the rand.

The remaining steps necessary to complete the shoe are the usual ones consisting in removing the patch 43, assembling the sole lining 50 and affixing a heel 51.

Since the disclosure of the foregoing in my 40 copending application No. 671,109, filed May 15, 1933, I have made valuable improvements in my original method which are disclosed in my copending application Serial No. 703,237 filed December 20, 1933, and the improvements in 45 means which are particularly illustrated in Figures 16 to 19 hereof.

I have found that a plate 60 may be removably substituted for the clamp 28 of the sole rounding machine; that a pattern or template 61 may 50 be substituted for the pattern 20; and that the parts 60 and 61 may be formed so as to depress the central area 35 of the ball portion of the sole in the act of clamping the sole leather in the rounding machine, thus eliminating the 55 swage or pressing die heretofore described.

To accomplish this, I provide the plate 60 with elevated areas 62—62 on its opposite faces, and recess the pattern 61 over the areas 63—63 of its opposite faces to provide complementary die portions for depressing material clamped between them over the central area of the ball portion of the sole a distance slightly greater than the thickness of the insole to be split therefrom. By providing the elevated areas and depressed areas on opposite faces of the parts 60—61, respectively, I am enabled to use the same parts for patterning and depressing soles for mated pairs of shoes by merely inverting the plate 60 and pattern 61 in the sole rounding machine.

It will be understood that the sole material 27 is clamped under pressure in the sole rounding machine between the plate 60 and pattern 61, thereby inflexing the sole material over the 75

central area of the ball portion of the sole to be rounded, and that the sole is then rounded in the machine by the blade 29 guided by the side edges of the pattern.

5 The sole thus formed and rounded may then be reinforced by the perforate backing strip 36 and split in the leather splitting machine above the bottom of its depressed area 35 to provide a rounded outsole and a perforate insole of 10 lesser thickness and equal area.

10 I have further found that, in the operation of clamping the sole material in the rounding machine, I may also define and initially form an insole of suitable size, smaller than the outsole, 15 by making a plate 60' (Figure 18) of a shape and size corresponding to the insole desired and providing it with a double edged blade 22'. The blade 22' is secured by screws 23' to the plate at the margins thereof and extends perpendicularly from the unelevated face portions 20 of the plate a distance corresponding to the thickness of the insole to be formed. In this manner the plate 60' is used to incise the sole material in much the same manner as the pattern 25 20 is employed, as heretofore described.

25 When the plate 60', carrying the blade 22', and the pattern 61 are used together, the sole material is inflexed over the area 35 thereof and the incisions 32 are cut therein to define an insole, 30 all in the act of clamping the sole material in the rounding machine. Subsequently, when the sole has been rounded and split above the depressed area 35 and within the depth of the incisions 32, as previously set forth, the outsole 35 portion 40 and complementary perforate insole portion 39 result. Thereafter, the upper may be affixed to the insole and the outsole assembled thereto as above described to provide a finished shoe.

40 In this manner, I have provided a very simple and inexpensive method and means for producing my improved complementary outsole and insole members without adding to the number of operations ordinarily necessary for their production, and with the further advantages of 45 minimized waste and insured perfection of sizing.

45 Many modifications in the method and means here taught will become apparent from this disclosure to those skilled in the art to which this invention relates and I desire, therefore, to have the foregoing considered merely illustrative of my invention as defined in the here appended claims which are restricted to my specific means, the method and improvements therein being claimed in my copending applications above referred to. Particular attention

is directed to a division of the earlier application filed October 23, 1934, Serial No. 749,562.

I claim:

1. A combination template and cutting die for patterning outsoles and initially forming insoles comprising a plate having its edges contoured to define the outsole of a shoe, a cutting blade carried by said plate curved to define a margin of an insole, said blade being positioned in appropriate relation to the contoured edges of the plate and extending from a face of the plate a distance corresponding to the thickness of the insole desired. 10

15 2. A combination template and cutting die for patterning outsoles and initially forming insoles comprising a plate having its edges contoured to define the insole of a shoe, said plate having a removably attachable edge extension portion the outer edge of which is contoured to define margins of an outsole, a cutting blade conforming to an edge of said plate and removably held between said plate and said extension portion, said blade extending from a face of the plate a distance corresponding to the thickness of an insole to be initially formed thereby. 20 25

3. A pair of clamping members for holding a sheet of sole material, said members being formed to comprise cooperating die elements adapted to depress a sheet clamped therebetween over a predetermined central area corresponding to the intermediate area of the ball portion of a sole to be 30 35 formed thereby.

4. A pair of clamping members for holding a sheet of sole material in a sole rounding machine, said members being formed to comprise cooperating die elements adapted to depress a sheet clamped therebetween over a predetermined central area corresponding to the intermediate area of the ball portion of a sole to be 40 rounded from said sheet. 45

5. The structure defined in claim 4; one of said members comprising a sole rounding pattern. 50

6. A pair of clamping members for holding a sheet of sole material, said members being formed to comprise cooperating die elements adapted to depress a sheet clamped therebetween over a predetermined area corresponding to the central area of the ball portion of a sole to be rounded from said sheet, one of said members having a blade carried thereby adapted to incise the sheet to define margins of an insole, and one of said members comprising a sole 55 rounding pattern.

FRED MACCARONE.
